UNITED STATES PATENT OFFICE.

JOHN S. MELLON, OF ST. LOUIS, MISSOURI, ASSIGNOR OF SIX-TENTHS TO G. W. LEWIS, OF SAME PLACE.

ELECTRO-THERAPEUTIC APPLIANCE.

SPECIFICATION forming part of Letters Patent No. 412,196, dated October 1, 1889.

Application filed June 22, 1889. Serial No. 315,253. (No model.)

To all whom it may concern:

Be it known that I, JOHN S. MELLON, a citizen of the United States, residing at the city of St. Louis, in the State of Missouri, have 5 invented a new and useful Improvement in Electrical Appliances, of which the following is a specification, reference being had to the accompanying drawings and claim.

My invention relates particularly to health-giving appliances, which are adapted to generate galvanism and to both induct and educt electrical currents in connection with the human system, and to equalize such currents between it and the earth.

15 The invention consists of one or more galvanic pairs made of metals, which are adapted to be excited electrically by the moisture of the human body acting chemically upon the differing kinds of metal in the couples, and 20 a metallic conductor or eductor for connecting such couples with the moist ground and with the body under treatment.

The accompanying drawings illustrate some mechanical devices for its construction.

25 Figures 1, 2, and 3 are views of different forms of it.

Similar letters refer to like parts throughout the several views.

It is well known that changes of conditions in matter cause changes in the electrical forces, and such changes are constantly occurring throughout nature. The human system is subject to such changes, whereby it at times is liable to be injuriously surcharged 35 with or minus in its normal healthy electrical condition.

The object of my invention is to cure various diseases and to restore and retain health by keeping the electrical conditions of our 40 bodies always in harmony with those of the earth, from which we have originated, so that a person in any part of a house may be in direct electrical contact with the moist earth, the same as if standing upon it.

45 In Fig. 1 the galvanic pair A is made of two sheets, one of copper C and one of zinc B. The copper overlaps the zinc, and they

are fastened together at one of their ends by rivets or otherwise. The ground-conductor D is a copper wire or any other suitable electrical conductor, and is properly attached to the copper and zinc pair. It extends from them down into and is buried in the moist earth. It may or may not have the ground-plant E attached to it.

50 In Fig. 2 the pair A is similar, except in its construction, to the pair in Fig. 1, the face of the zinc sheet B is laid on the copper sheet C, the ends of which fold over the zinc, and is adapted to be electrically excited by moisture from placing one hand on the copper and the other on its zinc plate.

55 Fig. 3 is a galvanic pair of handles united together by the conductor D.

C is of copper, and B of zinc, both made of 60 sheet metal. Each of the last two pairs named have the ground-connection D, with or without the plant E. These pairs may be made in any shape or form or size, and of any metals which are adapted to be excited electrically by the moisture of the hands or feet 65 and other parts of our bodies acting on the metallic couple, while the grounded end of the conductor D is in contact with the moist earth. By standing with the moist feet on 70 the pair, or holding the hands thereon, or holding the handles in the hand, galvanic currents are generated in them to supply any deficiency of electricity which may exist, and means is thus provided for all electrical currents to interchange and establish harmony 75 and equilibrium between our bodies and the earth. For invalid uses, where they are confined to beds in upper rooms, it is only necessary to lengthen and attach the conductor D 80 to suit the situation.

I am aware of other electrical appliances 85 which are applied to local parts of the body for the treatment of diseases—none of which, however, have any ground-connection. Such 90 I disclaim. I am confident, however, that much greater benefits would accrue to the afflicted from the use of such devices if they were used in connection with my invention.

What I claim as my invention, and desire to secure by Letters Patent of the United States, is—

A galvanic pair the electrodes of which are adapted to be artificially excited electrically by the moisture of any part or parts of the human system or that of any other organized life from its contact therewith, in com-

bination with a ground-conductor connecting the pair with the earth, substantially as described.

JOHN S. MELLON.
